(57) **CLAIM**

The ornamental design for a floating UV filter, as shown and described.

DESCRIPTION

FIG. 1 is a perspective view of a floating UV filter showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the floating UV filter where the floating UV filter is in a configuration of use; and,

FIG. 10 is another perspective view of the floating UV filter where the floating UV filter is in the configuration of use. The broken lines in the drawings depict portions of the floating UV filter that form no part of the claimed design.
